UNITED STATES PATENT OFFICE.

HUBERT SCOTT-PAINE, OF SOUTHHAMPTON, ENGLAND.

CONSTRUCTION OF BODIES OF FLYING-BOATS AND LIKE LIGHT VESSELS.

1,393,645.

Specification of Letters Patent.

Patented Oct. 11, 1921.

Application filed April 10, 1920. Serial No. 373,365.

To all whom it may concern:

Be it known that I, HUBERT SCOTT-PAINE, a subject of the King of England, residing at Southampton, in the county of Hants, England, have invented certain new and useful Improvements in the Construction of Bodies of Flying-Boats and like Light Vessels, of which the following is a specification.

This invention is for improvements in or

10 relating to the hulls of flying boats and like light vessels and has for its object to provide an improved construction which while of adequate strength is extremely light. Further, the construction is such that the hull 15 is capable of resilient distortion so that when alighting on the water, or when subject to other forces, the hull can spring or yield thereby materially reducing the effect of the shock. Also the construction is such as to 20 allow the maximum space in the interior of the hull for carrying capacity.

According to this invention, the body 25 of a flying boat or like light vessel is built up of longitudinal stringers set edgewise, 30 hoop-timbers formed as a continuous spiral inside said stringers extending across and secured to all of them, bent-timbers outside the stringers and also secured to all of them and a skin or covering outside the bent-timbers, there being no internal cross frames 35 or stiffening members in the body.

The skin-covering preferably consists of 40 planking arranged diagonally or longitudinally, or both, and it is secured to the stringers or bent-timbers.

Preferably the stringers are recessed at 45 their outer edges to receive the whole depth of the bent-timbers within them. The skin-planking preferably is made in portions of such dimensions that each portion extends from one stringer to the next adjacent stringer and there abuts the next succeeding portion, both portions being secured to the outer edge of the same stringer.

45 According to another feature of the invention the skin-planking is attached to the body framework so that each strip extends diagonally from one stringer to the next adjacent stringer and there abuts endwise the succeeding portion outside the said bent timbers and secured to the stringers and bent timbers.

According to another feature of the invention, a second skin-planking is formed 50 under the hull from a side wing on one side

of the body to a side wing on the other side of the body.

In the accompanying drawings, which illustrate the application of this invention to a flying-boat-hull,

Figure 1 is a half-section on a plane transverse to the longitudinal axis of the hull;

Fig. 2 shows a portion of Fig. 1 to a larger scale;

Fig. 3 is a perspective view showing a 65 method of attaching a side wing to the hull;

Fig. 4 is a partial side elevation showing the frame of a boat with a fabric skin attached, and

Fig. 5 is a perspective view of a part of 70 the hull showing the spiral formation of the hoop-timbers.

Like reference characters indicate like parts throughout the drawings.

Referring to Figs. 1 and 2, the hull of the 75 flying boat is of an approximately oval or egg-shaped cross-section. It is built up of a suitable number of longitudinal stringers 10 spaced apart around the curve of the section, the keelson 11 at the bottom constituting one of the stringers or being similar to them.

The stringers 10 are set edgewise so as to radiate or approximately radiate from the center line of the hull. Inside the 85 stringers and secured to all of them are timbers 12 which are in the form of hoops and will be referred to as hoop-timbers. These hoop-timbers 12 extend completely around the section of the hull, and where 90 the section is closed, they are preferably arranged as a continuous spiral. Where there is an opening in the upper part of the hull, as at the cock-pit, these timbers are separate from one another and extend from one edge 95 of the cock-pit around the lower part of the hull up to the other edge. In all cases, however, they are secured to the inner edges of all the stringers and to the upper edge of the keelson. The hoop-timbers may be 100 spaced somewhat closely together so as to provide a practically continuous surface on the interior of the hull, thereby avoiding the necessity for the provision of a continuous skin or deck.

105 The outer edges of the longitudinal stringers are recessed at 13 to receive the encircling timbers 14 which are referred to as bent-timbers, and these are suitably secured to each of the stringers and also to the outer 110

or lower surface of the keel which lies under the keelson.

The skin-planking for the hull, which may be arranged diagonally, or longitudinally, or both, is made up in short sections 15 which are of such a length that they extend from a stringer 10 to the next adjacent stringer, and form a butt joint, which is covered by the stringer inside with the next section or portion of planking. Each stringer 10 therefore has secured to it the two ends of adjacent sections of skin-planking. Obviously the skin-planking may also be secured to the bent-timbers 14, either where they lie within the recesses 13 in the stringers or elsewhere if it should be so desired.

Where the regular outline or contour of the hull is to be varied by projections such as side wings or steps, these projections are preferably formed separately and are built on to the outside of the continuous skin-planking of the hull proper. Such a projection is illustrated in Fig. 2 where a projection is shown as formed by a chine 16 supported upon suitable frame-members 17, 18. These frame-members are secured either directly to the hull, or to longitudinal members 19 secured thereto outside the skin-planking 15. The projection itself is provided with a suitable skin-planking 20 and may be reinforced as to its internal structure by struts 21 or bulkheads 22.

Generally there will be no objection to the use of bulkheads or frames for giving the requisite strength or stiffness to these wings, since the space in the interior thereof is not accessible from the interior of the hull and is therefore of no particular value as space. Preferably the skin-planking 20 on the underside of the projection is continued right around the bottom of the hull to meet the similar planking from the corresponding projection on the other side.

Figs. 3 and 4 show a modified construction for the attachment of a side wing to the hull. Fig. 3 shows a portion of the frame of the boat nearer the bow where the lateral projection or wing is of a different section. The wing is built with longitudinal stringers 23 similar to the main stringers 10, and these have secured upon them timbers 24 which are similar to the bent-timbers 14 and are secured to the main stringers 10 intermediate of them. Bulkheads 25 may be provided where desired. This construction differs from that previously described in that the skin-planking of the hull proper is continued out over the side wing or step, but if desired the space within the side wing may be shut off from the interior of the hull by means of a fabric or other similar skin. This modification is shown in Fig. 4 where a fabric covering 26 is secured on the outside of the bent-timbers 14 and stringers 10,

being perforated at 27 to permit the additional timbers 24 to pass through it.

When it is desired to reduce the weight of the hull to the greatest possible extent, the skin-planking 15 on the hull is omitted either in the construction illustrated in Fig. 2 or the construction illustrated in Fig. 3 and a fabric covering as shown in Fig. 4 is used.

The benefit of this fabric skin is that the hull is maintained water-tight even although the wing may be perforated or damaged. The close spacing of the bent-timbers and stringers provides sufficient support for the fabric to be a satisfactory water-tight skin in cases of emergency.

Additional longitudinal members 28 (see Fig. 1) similar to the stringers may be provided in the main hull, where desired for any special purpose, as for example at the point of attachment of a side wing to the hull, where such point of attachment does not coincide with a regular stringer 10.

Referring again to Fig. 1, if it is desired to provide for exceptional strength, the outer skin 15 may be duplicated by providing two sets of planking arranged at an angle to one another and in another modification a fabric skin may be stretched over the skin-planking of the hull, whether it is single or double, being securely cemented thereto. Where the skin-planking is double the fabric may be interposed between the two layers of planking.

It will be seen that this construction provides a body or hull in which no transverse bulkheads or structures are used, so that the maximum amount of space is available inside the hull for any purpose to which it may be desired to put it, and this result is achieved without sacrificing any of the strength of the hull, but it is in fact accompanied by an additional resilience of the hull which is particularly advantageous for flying-boats and like vessels.

What I claim as my invention and desire to secure by Letters Patent is:—

1. In a body for flying-boats and like light vessels, the combination of longitudinal stringers set edgewise, hoop-timbers formed as a continuous spiral inside said stringers extending across and secured to all of them, bent-timbers outside said stringers and secured to all of them, and a skin outside the bent-timbers.

2. In a body for flying-boats and like light vessels, the combination of longitudinal stringers set edgewise, hoop timbers formed as a continuous spiral inside said stringers extending across and secured to all of them, bent timbers outside said stringers and secured to all of them, and skin-planking, whereof each strip extends from one stringer to the next adjacent stringer and there abuts endwise the succeeding portion

outside said bent timbers and secured to the stringers and bent timbers.

3. In a body for flying-boats and like light vessels, the combination of longitudinal stringers set edgewise, hoop timbers formed as a continuous spiral inside said stringers extending across and secured to all of them, bent timbers outside stringers and secured to all of them, a continuous

skin-planking extending around the body, 10 side wing structures built on to the outside of the body and including a second skin-planking formed as a continuous sheet under the hull from a side wing on one side of the body to a side wing on the other side 15 of the body.

In testimony whereof I affix my signature.
HUBERT SCOTT-PAINE.
